UNITED STATES PATENT OFFICE.

EDWARD ERICKSON, OF BEVERLY, AND JOHN W. COSGROVE, OF MEDFORD, MASSACHUSETTS, ASSIGNORS TO UNITED SHOE MACHINERY COMPANY, OF PATERSON, NEW JERSEY, A CORPORATION OF NEW JERSEY.

CEMENTING-MACHINE.

1,170,520.

Specification of Letters Patent.

Patented Feb. 8, 1916.

Application filed February 13, 1913. Serial No. 743,267.

To all whom it may concern:

Be it known that we, EDWARD ERICKSON and JOHN W. COSGROVE, citizens of the United States, residing at Beverly, in the 5 county of Essex and State of Massachusetts, and at Medford, in the county of Middlesex, in the State of Massachusetts, respectively, have invented certain Improvements in Cementing-Machines, of which the following 10 description, in connection with the accompanying drawings, is a specification, like reference characters on the drawings indicating like parts in the several figures.

This invention relates to machines for applying coating material to stock and is 15 herein illustrated in connection with a machine for applying cement to pieces of fabric which are to be used to line the uppers of boots and shoes. In machines of this class 20 it is common to provide a cement applying roll of comparatively large diameter upon which the fabric may be lightly laid, nap side down, and from which said fabric may be removed to be placed upon a vamp or 25 other part of the upper of a shoe. It is desirable to coat the nap surface only of the fabric with just sufficient cement to cause it to adhere to the leather so that the nap may form a flexible connection between the 30 leather and the body of the fabric, the body itself not being wet with the cement and consequently not being stiffened when the cement has set.

One of the principal difficulties which has 35 arisen with machines of this class has been that the parts of the machine have become more or less covered with thickened cement mixed with particles of lint or other foreign matter. To prevent this, doctors, scrapers 40 and strainers have been used; but owing to the tendency of the cement to become gummy when exposed in small quantities to the air and to the fact that a certain amount of lint is transferred from the fabric to the machine, it is necessary to clean the parts of 45 the machine at intervals.

The general object of the present invention is to facilitate this cleaning; and to 50 this end one feature of the present invention consists of a readily removable receptacle upon which are mounted the doctor, the scraper, the strainer and the cement supply-

ing roll. It is thus possible by pulling the receptacle from beneath the cement applying roll to obtain ready access to the various 55 parts of the machine.

In machines of this class the bearings of the cement supplying roll are particularly troublesome, and a further feature of the invention consists in a machine of the class 60 described of open-sided bearings carried by the cement receptacle in which the trunnions of the supplying roll are received. With this construction, when the cement receptacle has been pulled out from beneath the cement 65 applying roll, the supplying roll may be lifted out of its bearings, cleaned and replaced therein without any manipulation of the parts whatever.

These and other features of the invention 70 including certain details of construction and combinations of parts will be described in connection with the accompanying drawings and will be pointed out in the claims.

Referring now to the accompanying draw- 75 ings, Figure 1 is a longitudinal section through a machine in which the present invention is embodied; Fig. 2 is a detail perspective of one end of the cement receptacle and the bearing which is pivoted thereto; 80 Fig. 3 is a perspective of an end of one of the trunnions of the cement supplying roll; and Fig. 4 is a perspective of the machine, the base having been broken off.

Slidably mounted in the base 1 of the ma- 85 chine and held in adjusted position by set screw 3 is a column 5 to the upper end of which is fast a supporting table 7 having a flat upper face upon which the cement receptacle 9 rests. This table is designed to 90 permit the application of heat and for this purpose has a socket to receive a heat unit 11 which may be connected with any suitable source of electricity. The table also carries a U-shaped length of steam pipe 13 which 95 may be connected to a source of steam; and either or both methods of applying heat may be used as desired.

The cement applying roll 15 is fast to a 100 shaft 17 which is rotatably mounted in uprights one of which is shown at 19. To the shaft 17 is fast a gear 23 which is driven through a pinion 25 from a driving shaft 27, said shaft being arranged to be clutched

when desired to a pulley 29 by the manipulation of a hand lever 31. The clutch itself will not be described further since the details of its mechanism form no part of this 5 invention. In order to supply cement to the applying roll 15 a cement supplying roll 33 is arranged to contact at its upper portion with the under portion of the applying roll 15 and to turn with its lower 10 portion dipping into the cement in the receptacle; and this supplying roll is formed at each end with raised portions 16 which determine the thickness of the coating of cement carried by said roll.

15 In the operation of the machine the applying roll 15 is rotated in a counter-clockwise direction as viewed in Fig. 1; and in order to regulate the thickness of the coating of cement which is carried by said roll, a 20 doctor 34 is fast upon studs 35 carried by the receptacle 9. To the right hand stud, as viewed in Fig. 4, is fast a lever 37 having a yoke to receive a pin 39 which is eccentrically mounted on a short shaft 41 25 provided with a handle 43 by which it may be turned to adjust the doctor 34 toward or from the applying roll 15. In order to hold the doctor in adjusted position an extension of the handle 43 carries a spring pressed 30 pin or stop 45 having a V-shaped end which is received in an arc-shaped groove, V-shaped in cross section, said groove being formed in a projection of one wall of the receptacle 9. In order to remove from the applying roll the lint and dirt which accumulate upon it, a resilient scraper 47 is located 35 as shown in Fig. 1, said scraper being fastened to one wall of a raised compartment the bottom of which is formed by a 40 strainer 49.

In machines of this class it is very desirable that ready access to the various parts be provided in order that the cleaning of the parts may be facilitated. The mounting 45 of the doctor, the scraper and the strainer upon the cement receptacle, as has been described above, permits ready access to these parts since the receptacle is so mounted that when the latch 52 is swung from the position occupied in Fig. 1 to that occupied in Fig. 2 the receptacle may be pulled out from beneath the applying roll 15. In order that the supplying roll 33 may be removed from the receptacle, said roll is provided at each 50 end with a trunnion 51 which is received in an open-sided bearing 53. Each bearing is pivoted upon a screw 55 which is threaded into an end wall of the receptacle, said bearing being urged upwardly about its pivot 55 by a spring 56, see Fig. 4, which rests upon an adjusting screw 57 and supports a plunger 59. The screw, spring and plunger are seated in a suitably shaped socket in a boss on the receptacle 9, and over each plunger 60 65 projects an ear 61 which is integral with the

open-sided bearing 53. With this construction the supplying roll 33 may be adjusted toward and from the applying roll by turning the screws 57, and after the rolls have been brought into contact the tension of the 70 springs may be varied.

In machines of this class with which cement is applied to fabric, a certain amount of lint is distributed about the machine, and this lint is particularly troublesome 75 when it gets into the small space between the ends of the trunnion 51 and the adjacent walls of the bearing 53. In order, then, to force such lint out of said space and thus prevent interference with the rotation of the 80 supplying roll, each trunnion is provided at its end with flaring grooves 65 which cross the radii of said trunnions. In the illustrated machine these flaring grooves are straight and are arranged obliquely to said 85 radii. The direction of rotation of the trunnions is indicated in Fig. 1, from which it will be clear that any lint which may be wedged against the end of a trunnion will be worked outwardly to the periphery of 90 said trunnion. In order to permit the escape of such lint, a passage 67 is provided in the lower wall of each bearing 53. When, therefore, a piece of lint gets wedged in between the end of a trunnion and the adjacent 95 wall of the corresponding bearing, it will be worked outwardly by the grooves 65 and finally forced into the passage 67.

In order to protect the cement from dirt and dust, a cover 69 of sheet metal may be 100 hung upon a flange of the doctor 34 as shown in Fig. 1. A second cover 63 is pivoted at the rear of the receptacle and extends partially over the compartment which contains the strainer.

In the operation of the machine power is applied to the shaft 27, and the applying roll 15 is thereby rotated slowly, said roll rotating the supplying roll 33 and causing the last named roll to lift cement from the 110 receptacle and deliver it to the applying roll. When it is desired to clean the machine the latch 52 is turned down to the position shown in Fig. 1 and the receptacle is pulled out from beneath the applying roll. 115 The supplying roll is then lifted out. The various parts of the machine which are liable to be covered with more or less hardened cement and bits of lint are thus readily exposed so that said parts may be cleaned very 120 quickly. After the cleaning has been accomplished, the supplying roll 33 serves as a stop to limit the inward movement of the receptacle, and when the receptacle has reached its inward position the scraper 47 125 and the doctor 34 are in operative relation to the applying roll 15.

Although the invention has been set forth in connection with a particular machine, it should be understood that the invention is 130

not limited in the scope of its application to the particular machine shown and described.

Having thus described our invention, what we claim and desire to secure by Letters Patent of the United States is: —

1. A machine of the class described having, in combination, a cement applying roll, a self contained receptacle for cement, a supplying roll adapted to transfer cement from said receptacle to said applying roll, a doctor for regulating the thickness of the coating of cement on said applying roll, a scraper for cleaning said roll, and a strainer 10 to which is directed the material removed from said roll by said scraper, said supplying roll, doctor, scraper and strainer being carried by said cement receptacle and being removable from the machine therewith.
- 15 2. A machine of the class described having, in combination, a cement applying roll, a readily removable receptacle for cement, open-sided bearings carried by the walls of said receptacle, a cement supplying roll having trunnions adapted to be received in said bearings, a doctor pivotally mounted on a wall of said receptacle and arranged to regulate the thickness of the coating of cement on said applying roll, a raised compartment in said receptacle having a perforated bottom, and a scraper mounted on a wall of said compartment.
- 20 3. A machine of the class described having, in combination, a cement applying roll, a receptacle for cement, open-sided bearings mounted upon the walls of said receptacle, and a cement supplying roll having raised portions at its ends and provided with trunnions adapted to be received in said 25 bearings.
- 30 4. A machine of the class described having, in combination, a cement applying roll, a readily removable receptacle for cement, open-sided bearings movably mounted upon the walls of said receptacle, springs carried by said receptacle and arranged to support said open-sided bearings, and a cement supplying roll having trunnions adapted to be received in said bearings.
- 40 5. A machine of the class described having, in combination, a cement applying roll, a readily removable receptacle for cement, open-sided bearings movably mounted upon the walls of said receptacle, springs carried by said receptacle and arranged to support 45 said open-sided bearings, and a cement supplying roll having trunnions adapted to be received in said bearings.
- 50 5. A machine of the class described having, in combination, a cement applying roll, a readily removable receptacle for cement, open-sided bearings movably mounted upon the walls of said receptacle, springs carried 55 by said receptacle and arranged to support

said open-sided bearings, a cement supplying roll having trunnions adapted to be received in said bearings, and means for adjusting said supplying roll toward and from said applying roll.

60

6. A machine of the class described having, in combination, a cement applying roll, a receptacle for cement, open-sided bearings carried by said receptacle, and a cement supplying roll having trunnions adapted to be received in said bearings, the ends of said trunnions being provided with grooves arranged to cross the radii of said trunnions.

65

7. A machine of the class described having, in combination, a cement applying roll, a receptacle for cement, open-sided bearings carried by said receptacle, and a cement supplying roll having trunnions adapted to be received in said bearings, the ends of said trunnions being provided with grooves arranged to cross the radii of said trunnions, said bearings being provided with passages to receive foreign matter forced outwardly by the action of said grooves.

70

8. A machine of the class described having, in combination, a table, a cement applying roll mounted above said table, a receptacle for cement slidably mounted upon said table, a cement supplying roll mounted in said receptacle and adapted to take cement from said receptacle and supply it to said applying roll, and a resilient scraper mounted upon the walls of said receptacle and arranged to be brought into contact with said applying roll when said receptacle is slid into place.

80

9. A machine of the class described having, in combination, a table, a cement applying roll mounted above said table, a receptacle for cement slidably mounted upon said table, a cement supplying roll mounted in said receptacle, a scraper and a doctor mounted upon the walls of said receptacle in position to coöperate with the surface of said cement applying roll when said receptacle is slid into place.
